UNITED STATES PATENT OFFICE.

LOUIS T. MEDHOLDT, OF ROCKFORD, ILLINOIS, AND LEWIS B. CARLSON, OF BOSTON, MASSACHUSETTS, ASSIGNEES TO S. A. WOODS MACHINE COMPANY, OF SOUTH BOSTON, MASSACHUSETTS, A CORPORATION OF MASSACHUSETTS.

CUTTER-GRINDING DEVICE.

Application filed February 14, 1924. Serial No. 692,886.

To all whom it may concern:

Be it known that we, LOUIS T. MEDHOLDT and LEWIS B. CARLSON, citizens of the United States, and residents, respectively, 5 of Rockford, in the county of Winnebago and State of Illinois, and Boston, in the county of Suffolk and State of Massachusetts, have invented an Improvement in Cutter-Grinding Devices, of which the following description, in connection with the accompanying drawings, is a specification, like reference characters on the drawings 10 representing like parts.

Our present invention relates to grinding devices, and more particularly to an improved cutter grinding device applicable for grinding cutters while such cutters are located in operable position in the machine.

In woodworking machines, and particularly in planing machines, the problem of keeping cutters sharp and in alignment is a serious one and one that has not been successfully solved. That is, in planing machines, the cutters are long and are held in operative position on a cutterhead that is carried on an arbor and it is necessary that such cutter be mounted in a cutterhead in balanced relation to the center of rotation of the cutterhead. Attempts have, therefore, been made to grind the cutters while such cutters are in position in the cutterhead and in the machine in which they work. This was heretofore performed by an emery wheel or oil stone slideable back and forth over the cutter and laterally by a rotating abrasive wheel of emery or carborundum which moved transversely of the machine and longitudinally of the cutters. This latter method was successful in that it reduced the number of settings required for the cutters, but still necessitated the frequent removal of the cutters from the cutterhead in order to reduce the amount of heel that was made by the frequent grindings. As is well known, a planing cutter, for example, will not work satisfactorily after the width of the heel of the cutter exceeds a predetermined amount, this amount being approximately $\frac{1}{32}$ ". As on certain kinds of wood the cutters wear quite rapidly, it will be obvious that it was necessary to frequently remove the cutters from the cutterhead.

Our present invention was designed to obviate the necessity of removing cutters from a cutterhead for the purpose of reducing the amount of heel thereon and we have, therefore, devised an improved means whereby the cutters may be ground to obtain any desired clearance and remove entirely, if necessary, the heel made thereon by frequent truing or jointings. In carrying out our invention, we have utilized the transverse guideway heretofore built into, or provided with, planing machine and have so constructed and arranged an improved grinder holding device as to permit the bringing of the grinding wheel of such cutter devices into any angle desired with relation to the cutters so as to obtain any clearance 70 of the cutter blades desired during the grinding operation.

In the accompanying drawings illustrating a preferred embodiment of our invention,

Fig. 1 is a front elevation;

Fig. 2 is an end elevation, partly in cross section;

Fig. 3 is a detail of a portion of the grinder holding device;

Fig. 4 is a plan view of Fig. 3;

Fig. 5 is a perspective detail of another portion of the grinder holding device, and

Fig. 6 is a detail showing the position of a grinding wheel with respect to the cutter whereby the heel may be reduced or entirely eliminated.

Referring to the drawings, 10 designates a portion of the framework of a planing machine on which is mounted, as shown in the dot and dash lines, an upright or pedestal 11, one of these uprights being located on either side of the machine. Also mounted on the framework 10 and shown in dot and dash lines by the numeral 12 are side members in which are located alined bearings (not shown) and in these bearings is rotatably mounted a shaft 13 on which is secured, in the usual and approved manner, a cutterhead 14. Circumferentially arranged about the cutterhead 14 and extending longitudinally thereof are slots 15 in each of which slots is arranged a backing plate 16 and a cutter 17. Cooperating with each slot 15 are a plurality of bolts 18, which bolts are employed to hold the spacing blocks 16 and

cutters 17 securely in position in the slots 15. On the uprights or pedestals 11 and in alignment with each other are lugs or ears 19 in which are rotatably mounted on pins 20 the 5 forwardly extending arms 21, these arms being spaced apart from each other and having formed integral therewith and at their forward end a transverse plate 22 bevelled, as shown, top and bottom 23 and 24 respectively. Slidably mounted on the bevelled portions 23 and 24 is a member 25 provided 10 on its rear face, top and bottom, with dovetail grooves 26 and 27 engaging with the bevelled portions 23 and 24 respectively. This member 25 is slidable longitudinally of 15 the member 22 and, therefore, is slidable longitudinally with respect to the cutters 17 or the sliding movement of the member 25 is parallel to the axis of the shaft 13. Preferably 20 the front face of the member 22 lies in a plane making an angle of approximately 15° to the vertical, as clearly shown in Fig. 2. The forward face of the member 25 intermediate its ends is provided with a vertical dovetail groove 28 in which is slidably 25 mounted the member 29. Formed integral with the upper end of the member 29 and extending rearwardly thereof is a member 30 drilled and tapped to receive a knurled 30 adjusting screw 31, the lower end of which bears against the top surface of the member 27 and which acts to maintain the member 29 in adjusted position in the member 27. Also formed integral with the member 29 35 and at the top end thereof is a member 32 which extends laterally outward from the member 29 and this member is drilled to receive the upper end of a screw 33. The upper end of this adjusting screw 33 is a rotatable fit in the member 32, and secured to the top end of the adjusting screw 33 by pin 34 is the knurled head 35 and by means of which the adjusting screw 33 may be rotated. Formed on the adjusting screw 33 below the 40 member 32 is a collar 36 and the collar 36 and lower end of the knurled head 35 engage with the member 32 to prevent longitudinal movement of the adjusting screw 33 in such member 32. The member 25 is drilled and 45 tapped at 37 to receive the threaded end of the adjusting screw 33. It will be obvious, from the above description, that the member 29 may be moved upward or downward in the dovetailed slot 28 by means of the adjusting screw 33 and that, when once adjusted, may be firmly held in such adjusted 50 position by means of the adjusting screw 31. Formed integral with the member 25 near the lower end thereof and extending outwardly forward at right angles thereto is a 55 cylindrical member 38 which is drilled or cored, as indicated at 39, for lightness. Numeral 40 designates a block, one face of which is provided with a groove 41 extending 60 transversely thereof of the same diam-

eter as the diameter of the member 38. Extending through said block on either side of a center passing perpendicularly through the block 40 and through the center of the cylinder, of which the portion 41 is a part, and 70 equally spaced from such center are arcuate slots 42. Numeral 43 designates a member through which extends a passage (not shown) in which is rotatably mounted the driving shaft 44 of an electric motor 45, current for 75 which is transmitted from any convenient source of power through conductors encased in the flexible conduit 46. Rotatably mounted on the lower end of the shaft 44 is an abrasive wheel 47, as is usual. One face 48 of the member 43 is plain and is perpendicular to a plane passing through the axis of the shaft 44. Formed integral with, and extending outwardly from, such face 48 are 80 spot faces 49, each drilled and tapped to receive bolts 50 which pass through the arcuate slots 42 in the member 40 and serve to hold the member 43 and attached motor 45 in adjusted position relative to the outwardly and upwardly extending member 38. It will be 85 obvious, from an inspection of the drawings, that, by means of the member 40 and bolts 50, the member 43 and attached motor 45 may be adjusted through a limited angle in any one of the multiplicity of planes lying 90 tangent to the cylindrical surface of the member 38. By this construction, therefore, I am enabled to so bring the abrasive wheel 47 with respect to the cutters 17 as to have a 95 line of cut of such abrasive wheel on the cutters at any desired angle. Assuming that the cutters 17 are sharp and in proper position with relation to the cutter head 14 and assuming that, after such cutters become 100 dull, they are ground, either by means of the abrasive wheel 47 or in any other desired manner, the heel designated by the numeral 51 in Fig. 6 becomes gradually wider and wider as successive truing or jointing operations take place and when the width of the 105 heel 51 exceeds a predetermined amount, approximately $3\frac{1}{2}$ in width, it is necessary to regrind, as distinguished from resharpen, such cutters. By means of our improved 110 device, we are enabled to bring the abrasive wheel 47 into such a position relative to the cutters 17, while such cutters are held in position on the shaft 13, as to cause such abrasive wheel to entirely, if desired, eliminate the heel 51, this being clearly illustrated in 115 Fig. 6. If desired, the device for holding the cutterhead 14 in position to maintain any of the knives 17 in operative position relative to the line of movement of the grinding device. This member may be secured to the portion 22 or to any convenient portion of the machine, but as this forms no part of our present invention, it has not been illustrated and will not be further described.

The operation of our improved device is as 120

follows, it being assumed that it is desired to grind cutters 17 so as to remove the heel 51 thereon and to perform this grinding operation while the cutters are held in operative position in the cutterhead 14 and while said cutterhead is in position on the driving shaft of a planer or other machine. The frame 21 with the element 22 thereon is swung about the pivots 20 and into position 10 relative to the cutterhead 14, as shown in Fig. 2. The shaft 13 is rotated so as to bring one of the cutters 17 into operative position with relation to the grinding device. The bolts 50 are now loosened and by grasping 15 the motor 45, the abrasive wheel on the end of the shaft 44 thereof may be moved into a position such, for example, as that shown in Fig. 6 where the entire heel 51 will be removed by the abrasive wheel 47, it being understood, of course, that the screws 31 and 33 20 are utilized to assist in the positioning of the abrasive wheel 47. After the abrasive wheel has been properly positioned, the bolts 50 are screwed up, thereby clamping the member 23 and motor 45 in proper adjusted position 25 on the upwardly and outwardly extending cylindrical member 38. Power is turned into the motor 45 and by grasping the said motor and the member 28, the operator 30 moves the entire device lengthwise on the member 22 and, therefore, longitudinally of the cutter 17. After one cutter 17 has been 35 properly dressed, the member 25 carrying the motor and abrasive wheel is moved clear of such cutter and the shaft rotated to bring the next succeeding cutter into position where the above operation is repeated, this operation being repeated for each of the cutters in the cutterhead.

40 While we have necessarily shown and described the preferred embodiment of our invention somewhat in detail, it is to be understood that we may vary the size, shape, and arrangement of parts within wide limits 45 without departing from the spirit of the invention.

Having thus described our invention, what we claim as new is:

1. In a device of the kind described, the combination of a framework, a transverse 50 slide plate formed integral therewith and at one end thereof, means for pivotally mounting said framework and transverse plate on a machine and permitting the moving of said frame and transverse plate into operative 55 relation with the cutterhead held in such machine, a holding frame slidably mounted on said transverse plate, a cylindrical member extending upwardly and outwardly from said frame, a grinding device, and means for 60 adjustably securing said grinding device on said upwardly and outwardly extending cylindrical member.

2. In a device of the class described, the combination of a framework, a transverse 65 plate formed integral with, and at one end thereof and lying at an incline to the perpendicular, means for pivotally mounting said framework and transverse plate on a machine and permitting movement thereof 70 about the pivot point and into operative relation to the cutter blades secured in a cutterhead in the machine, a frame slidably mounted on the transverse plate and capable of sliding movement transversely of the machine, a cylindrical member formed on, and extending upwardly and outwardly from, the frame, a grinding device, a shaft in said grinding device and extending downwardly toward said cutters, an abrasive wheel secured to, and rotatable with, said shaft, and means for securing the grinding device in 80 position on the upwardly and outwardly extending cylindrical member and permitting angular adjustment of the grinding shaft. 85

In witness whereof I hereunto subscribe my name this 23rd day of January, 1924.

LEWIS B. CARLSON.

In witness whereof I hereunto subscribe my name this 7th day of Feby., 1924.

L. T. MEDHOLDT.
